UNITED STATES PATENT OFFICE.

GEORGE L. ALLEN, OF WILMINGTON, NORTH CAROLINA.

CAR-LADDER.

1,109,100.

Specification of Letters Patent.

Patented Sept. 1, 1914.

Application filed September 4, 1912. Serial No. 718,528.

To all whom it may concern:

Be it known that I, GEORGE L. ALLEN, a citizen of the United States, residing at Wilmington, in the county of North Hanover, State of North Carolina, have invented certain new and useful Improvements in Car-Ladders, of which the following is a description, reference being had to the accompanying drawings, forming a part hereof.

10 My invention relates to an improved form of car ladder, and more particularly to that class of car ladders such as are used on box cars. The object of the present invention being to supply a ladder of simple design, 15 economical in its construction and superior to those forms such as are now used.

With the above and other ends in view the invention consists in the construction, combination and arrangement of parts as 20 herein described, illustrated in the accompanying drawings and claimed in the clauses of the concluding claim.

In the drawings Figure 1 illustrates a front view of my improved form of ladder 25 attached to a freight car. Fig. 2 is a side view of the same. Figs. 3, 4, 5, 6, and 7 illustrate two forms of supporting brackets. Fig. 8 is a top sectional view of my ladder. Figs. 9 and 10 are views of a modified form 30 of rung.

My improved form of ladder is composed of two side members or stiles 1. These stiles are made from what is commercially known as angle iron. Holes 2 for the rungs 35 3 to fit into and holes 4 for the bracket bolts 5 to extend through are drilled or gang punched in the above mentioned angle irons and by my particular construction all these holes occur, or are designed to occur, in a 40 single leg of the angle iron, thus in the construction of these stiles the angle iron is sheared to the proper length and the holes gang punched in a single operation.

The rungs 3 are made of round bar iron, 45 having a long straight portion which is the rung proper, near the end of said rungs a portion 8 is bent inward and it is this portion that extends through the holes 2 formed in the stiles, the small portion 9 which extends beyond the hole 2 of the stiles 1 is then bent outward against the inner face of said stiles, all of which is clearly illustrated in Fig. 8.

In assembling the stiles and the various 55 rungs thereon the two angles are so placed with relation to each other and the car wall

that the legs of the angles parallel to the car wall are outermost and thereby expose a broad exterior flat face 6, furthermore the inward extending leg has exterior faces 7 60 adjacent, the advantages of this construction being that there is no danger of wedging should a person's foot slip along one of the rungs as often occurs in climbing upon ladders of this class. 65

In Figs. 9 and 10 there is illustrated a modified form of rung which has the advantage that it can be attached to the stiles after the ladder has been attached in position upon the car wall. In this form of 70 rung the portion 9 which extends downward through the stile is bent upward and in a line perpendicular to the plane formed by the main rung portion and the downward extending portion 8. In order to attach one of 75 these rungs it is only necessary to slightly tip the rung in order to be slid into position, and having once been placed into position it is given a slight extra set in order to securely clamp it to the stile. 80

A bracket designed to attach the ladder to the car wall is shown in front and side view in Figs. 3 and 4 respectively, this particular bracket is adapted to fit within the acute angle formed by the two legs of the 85 angle iron, the said bracket is provided with a bolt hole extending therethrough to thereby allow the bracket bolt 5 to securely clamp the stiles to the car wall. The said bracket is furnished with a broad base in order to 90 provide for a large bearing surface.

Figs. 5, 6, and 7 illustrate another form of bracket, being made from a small length of a channel bar. The advantage of this bracket is that it is hidden by the angle 95 irons and does not require any extra wall space other than is necessary for the ladder proper.

I wish to emphasize the advantages of having all the holes necessary for the ladder 100 construction in one leg of the angle iron side members for by so designing it is possible to punch them in one operation and furthermore that leg of the angle which in the present instance sustains the bending moment 105 similar to the web in an eye beam, has no holes therein and whose area is accordingly not decreased thereby.

Having thus described my particular form of car ladder what I wish to claim as new 110 and original with me is:

1. A car ladder comprising a pair of

stiles each consisting of a strip of angle iron having one part parallel with the surface against which the ladder is placed and the other part at an angle to said surface, the 5 latter part being arranged with its free edge against said surface and serving to hold the parallel part of the angle iron away from said surface, said parallel parts being provided with rung openings and openings for 10 the bolts of the securing brackets, rungs having their ends in said rung openings, supporting brackets bearing at their outer ends against the parallel parts of the angle irons, and securing bolts extending through the 15 openings in the parallel parts of the angle irons and through the brackets.

2. A car ladder comprising a pair of stiles each consisting of a strip of angle iron having one part parallel with the surface 20 against which the latter is placed and the other part at an angle to said surface, the

latter part being arranged with its free edge against said surface and serving to hold the parallel part of the angle iron away from said surface, said latter parts being on the 25 inner edges of the parallel parts, said parallel parts being provided with rung openings and openings for the bolts of the securing brackets, rungs having their ends in said rung openings, supporting brackets bearing 30 at their outer ends against the parallel parts of the angle irons, and securing bolts extending through the openings in the parallel parts of the angle irons and through the brackets. 35

This specification signed and witnessed this 19th day of July A. D. 1912.

GEORGE L. ALLEN.

In the presence of—

R. HUNT,
C. L. MEISTER.
